UNITED STATES PATENT OFFICE.

HERMAN LANDGRAF, OF PHILADELPHIA, PENNSYLVANIA.

DESIGN FOR A CAP FOR SIPHON-BOTTLES.

SPECIFICATION forming part of Design No. 24,111, dated March 12, 1895.

Application filed August 25, 1894. Serial No. 521,343. Term of patent 14 years.

To all whom it may concern:

Be it known that I, HERMAN LANDGRAF, a citizen of the United States, residing in the city and county of Philadelphia, State of Pennsylvania, have invented and produced a new and original Design for a Cap for Siphon-Bottles, of which the following is a specification, reference being had to the accompanying drawings, being part thereof.

10 The leading feature of my design for the cap of a siphon bottle, is the dome-shape of said cap, two nozzles which rise from said dome, and a concave wall at or about the center of the top of the dome, joining the respective inner side walls of said nozzles.

15 Figure 1 represents a perspective view of a

cap for a siphon bottle embodying my design. Fig. 2 represents a top or plan view thereof.

In the drawings A designates a cap, and B and C designate nozzles which rise from the dome D of said cap. At the top of the dome at or about the center thereof is a concave wall E which joins the inner side walls of the two nozzles B and C as continuities thereof.

What I claim is—

25 The design for the cap, of a siphon bottle, substantially as shown and described.

HERMAN LANDGRAF.
